BEATING UP MECHANISM FOR LOOMS,
ESPECIALLY FOR MANUFACTURING
TERRY TOWELING

Gustav Berg, Glasgow, Scotland

Application April 1, 1950, Serial No. 153,359
In Great Britain April 7, 1949

5 Claims. (Cl. 139—26)

1

This invention relates to a beating-up mechanism for looms which is adapted to effect the production of pile fabric and in which the weft is only partially beaten-up for a given number of picks (for instance, two or three) and then is fully beaten-up on the next pick, thus tightly beating home that pick of weft and any previous partially beaten-up pick, referred to usually as a "loose pick," and simultaneously producing pile loops in the warps. Primarily the invention is intended for use in the manufacture of terry towelling, but it may also be found to be suitable for the manufacture of pile fabrics other than towelling.

In particular, the invention relates to beating-up mechanism of a previously proposed type in which the beating-up movement is transmitted to the reed structure by a thrust member which has an eccentric adapted, upon rotation, to vary the effective beating-up movement transmitted to the reed and in which eccentric-control means are provided for holding said eccentric in a predetermined position relative to said member and for causing rotation of the eccentric from said position when required.

According to the present invention, the eccentric-control means are so related to the eccentric that they bring it approximately into its dead centre position for the performance of each full beat-up.

Preferably, the eccentric, the means for holding it in position and the means for rotating it from such position are all aligned to act in the same plane.

An example of beating-up mechanism according to the invention is shown in the accompanying drawings, in which:

Fig. 1 is an elevation, being partly in section of the mechanism. Fig. 2 is a plan of components of the mechanism, being partly in section on the line 2—2 of Fig. 1. Those portions of Fig. 1 shown in section are sections on the line 1—1 of Fig. 2.

The mechanism includes the usual batten or sley comprising a reed structure 4 and swords 5, which are pivotally mounted at 6 in the stationary frame 7 of the loom. As usual, there are two swords 5, one at each end of the reed structure, but in the drawings only one sword and associated parts are shown. The beating-up mechanism also includes a rotary crank shaft 8 which is journalled as usual in bearings (not shown) in the frame 7 and which incorporates a crank pin 9 coupled by a connecting rod 10 to the associated swords 5, the connecting rod being the

2

thrust member through which each beat-up is transmitted from the shaft 8 to the reed structure 4. The eccentric by which the extent of the beating-up movement of the reed is varied is denoted by 11.

In the example shown, the larger end of the connecting rod 10 embraces strapwise the eccentric 11, of which the eccentric pin 12 is journalled in the manner of trunnions in bearings 10 provided by spaced formations 13 on the associated sword 5. The control means for holding and rotating the eccentric 11 include two plates 14 secured to opposite sides of the eccentric and formed to act jointly as a lever having in effect two arms. The plates 14 forming this two-armed lever both come between the spaced formations 13. One of said arms has a pivotal connection at 15 to the top end of a spring 16 which is anchored at its bottom end, at 17, to the sword 5. 20 The other of said arms has a hardened steel pin 18 adapted to form a pivotal connection with a nearly horizontal steel control rod 19 arranged above the eccentric and formed with a hardened hook 20 to engage the pin 18.

25 The lever constituted by the side plates 14 with the pin 18, the spring 16 and the control rod 19 with its hook 20 are the means whereby the eccentric 11 is held in position and is rotated therefrom. All of these parts are arranged in the same vertical plane as the crank 9 and connecting rod 10 this plane being represented by the line 4—4 in Fig. 2. Thus the actions of all of these parts on the reed structure 4 are in precise alignment, which ensures the most effective and efficient mode of operation and which avoids twisting stresses and distortion during the heavy thrust of each full beat-up.

30 Cam mechanism, or other selection means such as a jacquard or a dobby, is applied to the control rod 19 for moving it into or out of the level at which its hook 20 is engageable with the pin 18 to hold it. In the example the control of the rod 19 is effected by a cam 21 on a rotary shaft 22. The rod 19 is pivotally attached at one end 23 to one arm 24 of a bell-crank lever whose other arm 25 is pulled by a spring 26 to hold the lever 24, 25 and therefore the hook 20 in positions determined by a stop 27, which abuts against a bracket 28 on the loom frame 7. The 35 control rod 19 rests upon a cam-operated rod 29, a pin 30 on the control rod engaging in a slot 31 at the top of the cam-operated rod.

In operation, the beating up mechanism according to the example is timed so that the reed performs firstly a partial beat-up (giving

a loose pick) secondly another similar partial beat-up, and thirdly a full beat-up (giving a tight pick) as shown by Fig. 1. During each partial beat-up operation, the hook 20 is lowered by the action of the cam 21 and engages the pin 18, as shown by dash-dot lines in Fig. 1. Therefore the eccentric 11 is rotated clockwise by its lever 14, 14 against the pull of the spring 16 out of its normal position. In consequence of this rotational displacement of the eccentric 11, the reed 4 is withdrawn a short distance relative to the crank pin 9, so that only a partial beat-up is performed. Following the performance of two such partial beat-up operations, the hook 20 is lifted by the cam 11 clear of the pin 18, as shown in full lines in Fig. 1. Thus, the eccentric 11 is allowed to remain in its normal position, which is its dead centre position, and in this position the reed 4 is at its maximum distance from the crank pin 9, so that a full beat-up operation is performed. As Fig. 1 shows, at the limit of the beat-up movement, the centres 32 and 33 of the eccentric pin 12 and of the eccentric 11 itself are in the line of thrust of the crank and connecting rod, this line being the line 2-2 in Fig. 1. In other words, during the full beat-up action, the connecting rod 10 thrusts through the eccentric 11 as though both parts were a single rigid member. Thus, there is no tendency on the part of the eccentric 11 to become rotatably displaced under the thrust and so no extra burden is imposed on the spring 16 or the control rod 19. Moreover, this arrangement allows for a slight regulation to one or other side of the true dead centre without causing any appreciable variation in the limit of the beat-up movement, the only effect of such deviation being a negligibly small increase in the tension of either the spring 16 or the control rod 19.

Means for making such a small regulation of the limit of the full beat-up movement as may be required are provided, namely, an adjustment set-screw 34 which is secured to the lever plates 14 and contacts with the reed structure 4. Adjustment of the screw 34 is an act which is done more or less only when the loom is being first put into use, there being no need for further adjustment during normal operation.

The example shown represents an especially useful arrangement. It will be noted that the lever 14, 14 extends upwards from the eccentric and holds the pin 18 at a rather high level above the crank-and-connecting-rod mechanism. The control rod 19 also is arranged at a similar high level. Thus these parts 18 and 19 are quite remote from the other part applied to the lever 14, 14, namely the spring 16. This arrangement facilitates the location of the various parts on the same axis 1-1, Fig. 2.

The pile loops formed in the warps of the fabric being woven depend for their length upon the difference between a full beat-up and a partial beat-up. Seeing that the difference is determined by the size of the angle through which the eccentric 11 is rotated by the hook 20 preparatory to each partial beat-up, the length of the pile loops is determined by the location for the time being of the anchorage of the rod end 23.

It is a feature of the invention that the length of the pile loops is regulatable at the will of the operator, and therefore means are provided for adjusting the location of the anchorage, at 23,

about which the hooked rod 19 pivots. In the example the said adjustment means consist of the previously mentioned stop 27 and the abutment bracket 28. As shown in Fig. 1, the stop 27 is a set-screw which is carried by a bracket 35 on the lever arm 24. Seeing that the lever 24, 25 is a stationary component and seeing that the parts 23 to 27 are arranged out of the way of the working parts 8-14 of the beat-up mechanism, the operator can very easily adjust the set-screw 27 and in this way regulate the length of the pile loops as required for the fabric being woven. It will be manifest that only the part 27 requires adjustment in order to vary the loop length.

Virtually, adjustment of the part 27 has the same effect as though the anchorage 23 was permanently stationary on the length of the rod 19 was shortened or lengthened.

It has already been explained herein that for a full beat-up the eccentric 11 occupies its dead centre position, which is adjustable although only slightly by the set-screw 34. It will be appreciated that any angular adjustment of the eccentric 11 at the dead centre position corresponds to a notably non-equivalent, i. e. a comparatively slight, adjustment of the beat-up position of the reed structure 4. In contra-distinction, when the pin 18 is held by the hook 20 and the eccentric 11 is rotated through the substantial angle requisite for a satisfactorily diminished partial beat-up, the eccentric then occupies an angularly offset position in which any angular adjustment of the eccentric results in a somewhat equivalent adjustment of the beat-up position of the reed structure 4. That is to say, even a substantial adjustment by the screw 34 has only a comparatively slight effect on the final beat-up position of the reed structure 4, whereas a substantial adjustment of the screw 27 has an equally substantial effect on the beat-up position and is useful for regulation of the length of the pile loops.

In the loom, mechanism such as described is provided in association with each of the two swords 5 supporting the reed structure. A further advantage of the present symmetrical arrangement illustrated by Fig. 2 is that the parts for both sides of the loom are identical (that is, parts at opposite sides are not made to opposite hands) thus reducing the amount of spare parts required and so minimizing maintenance costs. Such similarity of parts applies not only to those shown in Fig. 2 but also to the control rod 19 and the parts 24-29 which support and actuate it.

I claim:

1. In a terry fabric loom comprising a reed structure, beat-up mechanism for operating the reed structure, a rotatable eccentric connecting said mechanism to the reed structure, a lever arm extending from the eccentric and a pivotal member for engaging said arm in order to rotate the eccentric between positions for transmission to the reed structure of a full beat-up and a partial beat-up, alternatively, the combination of means co-operating with said lever arm to hold the eccentric in one of its dead centre positions for transmission of a full beat-up, inter-engageable parts on said pivotal member and said lever arm arranged to rotate the eccentric into a position intermediate said dead centre positions to transmit a partial beat-up, and adjustable means in a location clear of the

working parts of the beat-up mechanism for adjusting said pivotal member at will in order to regulate the length of the pile loops by regulating the offset angular position of the eccentric for a partial beat-up.

2. In a terry fabric loom comprising a reed structure, beat-up mechanism for operating the reed structure, a rotatable eccentric connecting said mechanism to the reed structure, the eccentric being arranged in a vertical plane, a lever arm extending from the eccentric and a pivotal member for engaging said arm in order to rotate the eccentric between positions for transmission to the reed structure of a full beat-up and a partial beat-up, alternatively, the combination of means arranged to co-operate in said vertical plane with said lever arm to hold the eccentric in its dead centre position for transmission of a full beat-up and inter-engageable parts on said pivotal member and said lever arm arranged to rotate the eccentric into a position in which it is offset angularly from dead centre position by an amount sufficient to transmit a partial beat-up, both of said parts also being arranged in said vertical plane.

3. In a terry fabric loom comprising a reed structure, said structure including a sword at each end, beat-up mechanism for operating the reed structure, said mechanism comprising a crank and connecting-rod, a rotatable eccentric connecting said mechanism to the reed structure, a lever arm extending from the eccentric and a pivotal member for engaging said arm in order to rotate the eccentric between positions for transmission to the reed structure of a full beat-up and a partial beat-up, alternatively, the combination of a spring connecting said lever arm to said sword and striving to hold said arm with said eccentric in its dead centre position for transmission of a full beat-up, and inter-engageable parts on said pivotal member and said lever arm arranged to rotate the eccentric against the action of said spring into a position in which it is offset angularly from dead centre position by an amount sufficient to transmit a partial beat-up, said sword, crank and connecting rod, lever arm, spring and pivotal

member all being located and arranged to operate in one vertical plane.

4. In a terry fabric loom according to claim 3, a stop device arranged between the lever arm and the sword to determine the setting of the lever arm corresponding to the dead centre position of the eccentric, said device being adjustable to regulate said position.

5. In a terry fabric loom comprising a reed structure, beat-up mechanism for operating the reed structure, a rotatable eccentric connecting said mechanism to the reed structure, the eccentric being arranged in a vertical plane, a lever arm extending from the eccentric and a pivotal member for engaging said arm in order to rotate the eccentric between positions for transmission to the reed structure of a full beat-up and a partial beat-up, alternatively, the combination of means arranged to co-operate in said vertical plane with said lever arm to hold the eccentric in one of its dead centre positions for transmission of a full beat-up, inter-engageable parts on said pivotal member and said lever arm arranged to rotate the eccentric into a position intermediate said dead centre positions to transmit a partial beat-up, both of said parts also being arranged in said vertical plane and adjustable means in a location clear of the working parts of the beat-up mechanism for adjusting said pivotal member at will in order to regulate the length of the pile loops by regulating the offset angular position of the eccentric for a partial beat-up.
